UNITED STATES PATENT OFFICE.

FRANCIS L. BECKER, OF NEW YORK, N. Y.

DOOR-SPRING.

SPECIFICATION forming part of Letters Patent No. 354,087, dated December 14, 1886.

Application filed April 3, 1886. Serial No. 197,685. (Model.)

To all whom it may concern:

Be it known that I, FRANCIS L. BECKER, of the city of New York, county and State of New York, have invented a new and Improved Door-Spring, of which the following specification is a full, clear, and exact description.

This invention relates to a door-spring so made that as the door closes the force of the spring is increased. As usually made, the tension of the spring diminishes gradually as the door closes, and thus when the greatest force is required the least force is exerted. Therefore the door is apt to come to a standstill before being fully closed. By my invention this defect is remedied, the greatest force being exerted when the door is nearest its closed position.

The invention consists in the various features of improvement hereinafter more fully pointed out.

In the accompanying drawings, Figure 1 is a top view of my improved door-spring, showing the door closed. Fig. 2 is a similar view showing it partly open. Fig. 3 is a front view of the device, showing the door closed.

The letter A represents a door-frame, and B a door provided with my attachment. It consists of a curved lever, a, having a short arm, a', which is pivoted at or near its center to a base-plate, b, by pin c. The shorter arm of the lever a is attached to one end of a rod, d, the other end of which is secured to a bell-crank, e, pivoted to plate b.

f is a coiled spring, secured at one end to bell-crank e, and at the other end to a pin, g, passing through a projection of plate b. By means of a winged nut, h, embracing pin g, the tension of spring f may be diminished or increased. If desired, the lever a may be directly connected to spring f.

The plate b is attached to the door B by means of a slotted plate, i, screwed to the door and engaging a pin, j, projecting downward from plate b. In this way the attachment may be adjusted nearer to or farther away from the door to correspond to moldings on the door-frame. The attachment thus far described is secured to the door near the top, so that the horizontal lever a is placed above the upper edge of the door. To the upper edge of the door-frame A there is attached a friction-

roller, k, journaled to two lugs, l, connected to a back plate, m, which is screwed to the door-frame.

55

n is a light spring, attached with one end to plate b, and with the other end to the door-frame.

The relative position of the lever a and roller k should be such that when the lever is 60 swung back on opening the door the free end of the lever will clear the roller, while when the door is closed the free end of the lever is passed back of the roller.

The operation of the device is as follows: 65 The door being closed, the lever a is swung forward and rests back of roller k, Fig. 1. On opening the door, the lever, being forced against roller k, will be turned on its pivot c, and will be swung back until it assumes a position substantially at right angles to that originally occupied. A stop, o, on plate b

limits the backward motion of the lever. During this motion the spring f will have become 70 distended and will be locked in its distended position as soon as the lever a comes to rest against the stop o, this being the position indicated in Fig. 2. The door may now be fur-

ther or fully opened without altering the relative arrangement of the parts, excepting to dis- 80 tend the spring n. After the door has been released, the spring n will throw it back suffi- ciently far to bring the free end of lever a di- rectly back of roller k. As the end of the lever now comes in contact with the plate m, it 85 is thrown out of its position of rest, and the spring f will rapidly swing it forward into the position shown in Fig. 1. During this motion the lever will bear against the roller k, and thus close the door. It will be observed that 90

during the last-described movement of the parts the force with which the lever bears against the roller is continually increased. This is caused by two reasons: First, the free 95 end of the lever passing gradually farther and farther away from the roller, the latter to an even extent approaches the pivot c, and the amount of leverage exerted upon the roller is thereby increased; secondly, as the shorter lever-arm swings from the position shown in 100 Fig. 2 to that shown in Fig. 1, the spring f is increased in effectiveness, because the shorter lever-arm gradually assumes a position at right angles to the spring.

It will be seen that the spring *n* serves to throw the lever *a* into engagement with roller *k*, while the spring *f* serves to operate the parts after such engagement has been effected.

5 The spring *n* may possibly be omitted; but then the door must be partly closed by hand.

I claim as my invention—

1. The combination of lugs *l*, rigidly attached to door-frame A and carrying roller *k*, with plate *b*, attached to door B, and with curved lever *a*, having arm *a'*, pivoted at its center to plate *b*, and with spring *f*, connected to arm *a'*, substantially as specified.

2. The combination of lever *a* and plate *b*

with spring *f*, connected to lever *a*, and with stop *o*, and roller *k*, journaled to lugs *l*, substantially as specified.

3. The combination of lever *a* and plate *b*, having stop *o*, with springs *f* *n*, and with the roller *k*, journaled in lugs *l*, the whole operating substantially as specified.

4. The combination of lever *a* and plate *b*, having pin *j*, with spring *f*, and with slotted plate *i*, and roller *k*, substantially as specified.

FRANCIS L. BECKER.
